(57) **CLAIM**

The ornamental design for a bed, as shown and described.

DESCRIPTION

FIG. 1 is a front, right, top perspective view of a bed showing my new design;

FIG. 2 is a rear, left, top perspective view thereof;

FIG. 3 is a front view thereof;

FIG. 4 is a rear view thereof;

FIG. 5 is a right side view thereof;

FIG. 6 is a left side view thereof;

FIG. 7 is a top view thereof;

FIG. 8 is a bottom view thereof; and,

FIG. 9 is an enlarged partial perspective view of a front, right, top corner of the bed.

The broken lines in the drawing illustrate portions of the bed that form no part of the claimed design.
